United States Patent Office

Des. 183,818
Patented Oct. 28, 1958

183,818

PLATE OR SIMILAR ARTICLE

Shuzo Terano, Mizuho-ku, Nagoya, Japan

Application December 20, 1956, Serial No. 44,272

Term of patent 3½ years

(Cl. D44—15)

The figure is a plan view of a plate or similar article, showing my new design.

The plate is of a conventional configuration when viewed from the side and bottom thereof.

I claim:

The ornamental design for a plate or similar article, substantially as shown and described.
